UNITED STATES PATENT OFFICE.

JOHN I. BELLAMY, OF BROOKFIELD, AND RODNEY G. RICHARDSON, OF CHICAGO, ILLINOIS, ASSIGNORS, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed August 24, 1925, Serial No. 51,938. Renewed January 25, 1929.

The present invention relates to automatic telephone systems in general, but it is concerned more particularly with systems of this type in which directors are employed to 5 properly route the calls.

Directors that are used for routing calls to the proper offices are ordinarily each provided with a separate distributing frame at which the connections are made to secure 10 any desired routing of the calls. As the various senders of the directors operate independent of each other, the above arrangement is the simplest from a circuit standpoint. From the standpoint of economy, 15 however, a better arrangement is one in which the intermediate distributing frame is common to a plurality of directors. Furthermore, this latter arrangement enables the routes over which certain calls are handled to be conveniently and quickly changed from time to time as the conditions may require. It is with the common intermediate 20 distributing frame type of director that the present invention concerns itself.

One object of this invention is to provide 25 a director system in which a given office code digit is determined by one or more impulses transmitted over a single wiper of the office register, thereby permitting the number of 30 wipers on the office register in a system of this type to be maintained equivalent to the maximum number of office code digits.

In order to carry out and to attain the 35 above object, each director has been provided with a translating mechanism for controlling a registering device, consisting of four relays in the present case. This translating device may be operated in any one of a number of different ways (twelve in the 40 present case) over each wiper of the office register successively to set repeatedly the registering device in the director to control the transmission of the desired digits.

As one of the prime requisites of a system 45 of this kind is that no unwarranted delay shall take place, the registering device is set quickly according to a predetermined code rather than by ordinary non-coded impulses. This enables the relay register to be set 50 quickly to start the transmission of the first office code digit without undue delay and it enables the register to be reset for each following digit during the usual interval between successive operations of the sender, it 55 being understood that the successive opera-

tions of the sender are spaced apart sufficiently to permit the change-over and trunk hunting operations of the automatic switches to take place.

Another object of the invention is the production of a suitable arrangement whereby the office register, which is used only while the office digits are being registered and while the code digits are being retransmitted, may be restored to the common use 60 of the directors as soon as the last office code digit has been transmitted, instead of the usual arrangement according to which an office register is an integral part of each director. 65

In order to carry out the above object, each director is provided with an office register selector, which is operated to select an idle office register when the director is taken 70 for use and which is released to release the office register when the last office code digit is transmitted.

The other objects and features of the invention have to do for the most part with the circuit details involved in carrying out 75 the foregoing, and they may be gathered best from the description which is to follow.

Referring now to the drawings comprising Figs. 1-9, Figs. 1-6 show by means of the usual circuit diagrams a certain amount of equipment in a telephone system embodying the principles of the invention; Figs. 7 and 8 show two desirable modifications; and Fig. 9 is a table showing the code according 80 to which the digits are transmitted from the common sending drum to the directors. 85

In order for the drawings to be understood best, Fig. 3 should be placed below Fig. 1, with Fig. 2 to the left of Fig. 3; Figs. 5 and 6 should be placed below Figs. 2 and 95 3, respectively; and Fig. 4 should be placed to the left of Fig. 5.

Fig. 1 shows the trunk circuit TC inserted in the associated trunk line between the bank contacts 2-4 of a line switch and the selector S. This drawing shows also the director selector DS individual to the trunk circuit TC. This director selector has access to a number of directors, one of which is shown in Figs. 3-6. 100

The portion of the director shown in Fig. 2 comprises the sequence switch S which distributes the setting impulses to the various register switches, together with the sequence switch S' which places the com- 105 110

mon sending mechanism under the control of the various registers in the proper order.

The portion of the director shown in Fig. 3, comprises the sending switch SS which 5 cooperates with the pick-up and stop relays 241 and 242 to transmit the impulses as predetermined by the setting of the registers. This drawing shows also the control and translating relays 231-239 and the release relay 240.

Fig. 4, shows the office register OR which is common to a plurality of directors. This drawing shows also the common sending drum 301 which transmits impulses to the 15 several directors. Furthermore, this drawing shows the intermediate distributing frame IDF at which the connections between the multiply connected bank contacts of the office registers and the brushes of the drum 20 301 are made as desired.

The portion of the director shown in Fig. 5, comprises the relay register consisting of the relays 419-422 and the office register selector ORS, which selects an idle office 25 register when the associated director is seized, and which is released to free the office register when the proper time arrives.

The portion of the director shown in Fig. 6 comprises the digit registers DR-1-DR-30 4 which register the four subscriber digits in order to control the sending mechanism to subsequently retransmit them.

In order that the operation of the apparatus may be understood best, the way 35 in which a call is handled will now be explained.

Assuming that the trunk circuit TC, Fig. 1, is seized at the terminals 2-4 by a calling line switch, line relay 8 which is connected through armatures 16 and 18 and their resting contacts to conductors 5 and 7 pulls up over the calling line and closes at armature 11 a circuit for release relay 9. Release relay 9 energizes and grounds 45 the release trunk conductor 6 at armature 13. At armature 14 a circuit is closed for relay 19 of the director selector DS and the stepping magnet 20 in series, and at armature 15 the test wiper 27 of the director selector DS, which is connected through armature 23 and its resting contact to the working contact of armature 15, is connected to the junction of relay 19 and stepping magnet 20. Accordingly, stepping magnet 20 operates in a buzzer like manner 55 to advance the wipers 25-28 in case the director associated with the bank contacts on which the wipers are standing is busy. In this case relay 19 is short circuited by 60 the ground potential picked up by test wiper 27 to drive the magnet 20 and does not energize. When an idle director is reached, for example the one shown in the drawing, the operation of stepping magnet 20 ceases and relay 19, being no longer short circuited,

energizes in series with stepping magnet 20. Stepping magnet 20 does not energize at this time owing to the relatively high resistance of relay 19. Relay 19 at armature 70 24 prepares the operating circuit; at armature 23 it opens the test circuit and grounds test wiper 27; and at armatures 21 and 22 it connects the conductors 5' and 7' of the selector S to the wipers 25 and 26, with the result that relay 41 of the selector S 75 energizes over conductors 29 and 30 of the seized director and through the sending contacts 243 in multiple with the resting contact and armature 286. Relay 41 of the selector S at armature 51 closes a circuit for 80 the release relay 42 which energizes and prepares the switch for operation in the usual manner.

In the seized director, when the release trunk conductor 31 is grounded through the 85 test wiper of the director selector DS, release relay 240 energizes. At armatures 280, 281, 282, and 283 relay 240 removes ground from the release conductors 204, 205, 206, and 218; at armature 284 it places ground 90 on the locking conductor 217; and at armature 285 it prepares a circuit for pick-up relay 232. As a further result of its energization, relay 240 at armature 279 closes a circuit through armature 262 and its resting 95 contact and conductor 203, extending across Figs. 2 and 5, for relay 402 of the office register selector ORS and stepping magnet 401 in series. At the same time, relay 240 at armature 278 connects test wiper 406 of the 100 office register selector ORS, Fig. 5, to the junction of relay 402 and stepping magnet 401 through armature 414 of relay 402 and its resting contact, conductor 201, armature 278 and its working contact, armature 261 105 and its resting contact, and conductor 202. Relay 402 energizes in case the office register on which the wipers 403-410 are standing is idle, but it is short circuited and prevented from energizing in case this office register is 110 busy, in which case the wipers of the office register selector ORS are advanced step by step in the usual manner by the self interrupting stepping magnet 401, which operates from the ground picked up by the test 115 wiper 406.

When an idle office register is reached, for example the office register OR, Fig. 4, test wiper 406 encounters an ungrounded test contact, whereupon the operation of magnet 120 401 ceases. When this occurs relay 402, being no longer short circuited, energizes in series with stepping magnet 401, stepping magnet 401 not energizing at this time on account of the relatively high resistance of relay 402. Upon energizing, relay 402 disconnects test wiper 406 from the junction of its own winding and that of magnet 401 and connects it to the grounded conductor 203, thereby placing a ground potential through 125 406.

the test wiper 206 on the test conductor 354 of the office register OR; connects up the wipers 407-410 at armatures 415-418. The connecting up of wiper 403 at armature 411 results in the extension of the operating circuit to the vertical magnet 343 of the office register OR. Accordingly, the calling subscriber hears the dial tone which is placed on the vertical magnet circuit of the office register OR by the dial-tone transformer 307 which is common to a plurality of the office registers. The tone current generated in the left hand winding of the transformer 307 passes through the vertical magnet 343, conductor 351, bank contact and wiper 403, armature 411 and its working contact, conductor 121, bank contact and wiper 109, relay 101, conductor 32, bank contact and wiper 28, armature 24 and its working contact, and condenser 33 to the lower heavy talking conductor 7 through the resting contact and armature 18.

When the calling subscriber hears the dial tone which reaches his line over the above traced circuit, he starts to manipulate his calling device in accordance with the various digits of the desired number.

When the first digit is dialled, line relay 8 falls back a number of times corresponding to such digit. Each time it falls back it closes at the resting contact and armature 12 a circuit for the vertical magnet 343, Fig. 4, through the working contact and armature 24, wiper 28 and the bank contact on which it is standing, conductor 32, series relay 101, wiper 109 of the sequence switch S, conductor 121, working contact and armature 111, wiper 403 and the bank contact on which it is standing, conductor 351, and vertical magnet 343 to battery through the left-hand winding of the transformer 307. By the operation of vertical magnet 343, the wipers 339-342 are raised step by step until they stand opposite the desired level of bank contacts. Relay 101, Fig. 2, is energized in series with the vertical magnet on the first impulse of current delivered to the latter, and, being slow acting, maintains its armature attracted throughout the series of impulses. At armature 103 relay 101 closes a circuit for relay 102 which energizes and prepares at armature 104 a circuit for the stepping magnet 105 of the sequence switch S.

At the end of the series of impulses, relay 101 falls back and completes the stepping magnet circuit at armature 103, whereupon magnet 105 advances the wipers 108 and 109 one step. Wiper 109 disconnects the impulse conductor from conductor 121 and connects it to conductor 122. After an interval relay 102 falls back and opens the circuit of relay 105 at armature 104.

When the next digit is dialled, the impulses of current are delivered over con-

ductor 122 and through the working contact and armature 412, wiper 404, the bank contact on which it is standing, and conductor 352 to the rotary magnet 344 of the office register OR. By the operation of rotary magnet 344, the wipers 339-342 are rotated step by step until they come into engagement with the desired set of bank contacts, for example the set comprising contacts 331-334, representing the exchange in which the called line terminates.

Relay 101 is again energized and cooperates with relay 102 to operate magnet 105 to again advance the wipers 108 and 109 one step. Magnet 109 shifts the impulse conductor over to conductor 123 leading the operating magnet 501 of the digit register DR-1, Fig. 6. Wiper 108 places battery on the start conductor 208 with the result that the retransmission is started in a manner to be pointed out subsequently.

When the next digit is dialled, magnet 601 of the digit register DR-1 is operated over conductor 123 to set the associated wiper on the bank contact corresponding to the digit dialled.

Similarly, the digit register DR-2 responds and records the second subscribed digit; the digit register DR-3 responds and records the third subscriber digit; and the digit register DR-4 responds and records the fourth subscriber digit. The wipers 108 and 109 of the sequence switch S are of course advanced one step following each of the digits with the result that wiper 109 is advanced to a dead contact following the last digit. The wipers remain in this position until the director is released.

Returning now to the point at which the start conductor 208 is grounded, as soon (after this occurs) as the common sending drum 301, Fig. 4, arrives in the pick-up position shown in the drawing, ground through the brush 322 is placed on the pick-up brush 304 and is extended to the pick-up relay 232, Fig. 3, over the common pick-up conductor 216 through armature 252 and its resting contact, the resting contact and armature 290, armature 285 and its working contact, resting contact and armature 275, and armature 273 and its resting contact to the pick-up relay 232. Since the other terminal of relay 232 is connected to battery through start conductor 208, relay 232 energizes and locks itself at armature 265 through relay 238, and the resting contact and armature 277 to the grounded locking conductor 217. Relay 238, which is included in this locking circuit, does not energize at this time, however, on account of the fact that it is short circuited by the ground potential applied to the initial circuit of relay 232. As a further result of its energization, relay 232 closes at armature 267 a circuit through the resistances 237 and 130

236 in series so as to place a derived neutral potential on the right-hand terminal of the polarized relay 235; at armature 266 it connects the left-hand terminal of the polarized relay 235 through the resting contact and armature 264 and conductor 209 to the distributing wiper 113 of the sequence switch S'; and at armatures 268 and 269 connects up the switching conductors 214 and 215 to the corresponding relays 233 and 234.

A moment later, the further rotation of the drum 301 brings the first vertical insulated strip under the brushes, removing ground from the pick-up brush 304. When this occurs the locking circuit of pick-up relay 232, Fig. 3, becomes effective because the initial circuit is broken and relay 238, which is included in this locking circuit, energizes and opens at armature 273 a further point in the initial circuit of relay 232 and prepares a circuit for stop relay 239.

As the drum 301 rotates further, the various brushes are connected to battery or ground (- or +) potentials according to the table shown in Fig. 9. In this case it is assumed that the wipers 339-342 of the office register OR are set on the bank contacts 331-334. It will be noted that the first bank contact 331 is cross connected on the intermediate distributing frame IDF to the #9 brush 319, corresponding to the digit 9. By referring to the table shown in Fig. 9, it will be noted that the digit 9 is represented by a single positive impulse delivered in the second positive-impulse position.

Considering now the rotation of the drum in detail, after it has gone through the pick-up position, the drum goes through the first positive position without producing any result that affects the present call. The first positive position corresponds to the A relay 419, Fig. 5, and the positive contact of the polarized relay 235 is normally connected through armature 27 and its resting contact 45 and conductor 210 to the right-hand winding of the A relay 419. In this case however the A relay is not to be operated, and accordingly, no positive impulse is transmitted to relay 235, in the first positive position of the drum.

When the first negative position of the drum is reached, which position corresponds to the B relay 420, Fig. 5, the switching brush 302 of the drum 301 encounters a ground potential which is transmitted over conductor 214 and through armature 268 and its working contact to the positive switching relay 233 which disconnects the positive contact of the polarized relay 235 from the A relay 419 and connects it by way of conductor 213 to the C relay 421. The first negative position of the drum corresponds to the B relay 420, Fig. 5, to which the negative contact of relay 235 is normally connected through armature 271

and resting contact and conductor 211. Relay 420 does not operate because brush 319 does not encounter any potential source in the first negative position.

When the drum 301 arrives in its second positive position, ground (+ battery) is placed on brush 319 and is extended over the jumper 323 through bank contact 331, wiper 339, conductor 355, bank contact and wiper 407, armature 415 and its working contact, conductor 127, contact and wiper 113, conductor 209, armature 264 and its resting contact, armature 266 and its working contact, and relay 235 to the junction of resistances 236 and 237, which represents a neutral point of the exchange battery. Accordingly, relay 235 operates to place ground on its positive contact, thereby closing a circuit through armature 270 and its working contact, and over conductor 212 for the right-hand winding of relay 421. Relay 421 energizes and locks its left-hand winding to the locking conductor 217, at the same time shifting its right-hand armatures to effect the necessary circuit changes.

As a further result of the arrival of the drum 301 in its second positive position, ground is placed on the negative switching wiper 303 and is extended over conductor 215 and through armature 269 and its working contact to the negative switching relay 234. Relay 234 therefore energizes and disconnects the negative contact of the polarized relay 235 from the B relay 420 and connects it instead through conductor 213 to the D relay 422 preparatory to the arrival of the drum 201 in its second negative position.

When the drum 301 leaves the second positive position and goes into the second negative position, the ground is removed from wiper 319, whereupon the polarized relay 235, Fig. 3, assumes the normal position shown in the drawing, opening the circuit of the right-hand winding of relay 421, but relay 421 remains energized through its locking circuit which includes its left-hand winding. It will be noted that no circuit is closed over wiper 319 in the second negative position of the sending drum 301.

The drum 301 continues to rotate with the result that the pick-up position is reached the second time and the pick-up wiper 304 is again grounded. When this occurs, a second impulse is transmitted over the pick-up conductor 216 which at this time passes through armature 252 and resting contact and the working contact and armature 290, armature 285 and working contact, resting contact and armature 275, armature 273 and its working contact, and the normally closed contacts controlled by armature 276 to relay 239. Relay 239 energizes and locks itself to conductor 217 at armature 276, opens its initial circuit at armature 275 so as to prevent the circuit of the pick-up relay 232

from being again closed until the proper time arrives; and at armature 277 opens the locking circuit of pick-up relay 232. When this occurs relays 238 and 232 fall back, and relay 238 prepares a circuit for pick-up relay 232. Relay 232 restores the associated circuits to the normal position shown in the drawing.

As a further result of the energization of the stop relay 238, at armature 274 it connects the interrupter 115 (which is connected to the working contact of armature 274 through armature 117 and resting contact, and conductor 118) through the resting contact and armature 292 to the stepping magnet 245 of the sending switch SS. Stepping magnet 245 now energizes and deenergizes under the control of the interrupter 115. Upon its first energization, magnet 245 moves the associated pawl into engagement with the next notch in the wiper-driving ratchet wheel but does not move the associated wipers, and at the contacts 243 opens a point in the outgoing control circuit, including conductors 29 and 30, leaving the outgoing control circuit closed through the resting contact and armature 286 of the pick-up relay 241.

Upon the following deenergization of magnet 245 the wipers 246 and 247 are advanced one step. Wiper 247 engages a dead contact, but wiper 246 engages a grounded contact with the result that pick-up relay 241 energizes. At armature 286, relay 241 opens the associated point in the outgoing control circuit, leaving the outgoing control circuit now closed only at the sending contacts 243; it places an additional ground on the release trunk conductor 31 at armature 287 so as to hold release relay 241 energized until the sender again reaches its normal position in case the calling subscriber hangs up his receiver prematurely; and at armature 288 it closes a circuit for the magnet of the sequence switch S' through armature 293 and its resting contact and over conductor 207. Magnet 110 energizes preparatory to advancing the wipers 112 and 113.

Upon the next energization of magnet 245 the outgoing control circuit is opened at contacts 243, armature 286 having been operated as above stated. The control circuit is again closed at contacts 243 when magnet 245 falls back. The wipers are advanced another step and wiper 247 at this time engages the first impulse stop conductor, but, since this stop conductor is not grounded at this time, this operation does not result in the energization of stop relay 242.

The operation of the sending switch SS continues as described until nine interruptions have been produced in the outgoing control circuit at the sending contacts 243.

The ninth interruption is produced with the wiper 247 standing on the bank contact asso-

ciated with the eighth impulse stop conductor. When magnet 245 falls back and terminates the ninth interruption in the outgoing control circuit and advances the wipers 246 and 247 another step, wiper 247 engages the bank contact in which the ninth impulse stop conductor terminates, thereby closing a circuit for stop relay 242 as follows: From ground by way of the right-hand armature and resting contact of relay 419, Fig. 5, right-hand armature and its resting contact of relay 420, right-hand armature and its working contact of relay 421, second armature (counting from the right) and its resting contact of relay 422, the ninth impulse stop conductor, the corresponding contact in the bank of the sending switch SS, wiper 247 and stop relay 242 to battery. Stop relay 242 energizes over this circuit and places a shunt around the sending contacts 243 at armature 291; at armature 292 it disconnects magnet 245 from the interrupter 115 and closes the restoring circuit; at armature 293 it opens the circuit of the stepping magnet 110 of the sequence switch S'; at armature 294 it removes ground from the locking conductor 217; and at armature 295 it opens a point in the pick-up circuit of pick-up relay 232. Responsive to the closure of the above mentioned restoring circuit of magnet 245 at armature 292 and its working contact, magnet 245 obtains ground from the wiper 246 through the self-interrupting contacts 244 and spins the wipers 246 and 247 around to the position shown in the drawing. This operation opens the circuit of the slow acting pick-up relay 241, which by virtue of its slow action remains operated for an interval.

Responsive to the opening of the circuit of stepping magnet 110 of the sequence switch S, armatures 112 and 113 are advanced one step and wiper 113 disconnects the associated control conductor 209 from the first wiper 339 of the office register OR and connects it by way of conductor 128 to the second wiper 340 of the office register.

As a result of the removal of ground from conductor 217 at armature 294 relay 239, Fig. 3, falls back and prepares the pick-up circuit of relay 232, and relay 421, Fig. 5, falls back and removes ground from the ninth impulse stop conductor.

Responsive to the nine interruptions in the outgoing control circuit, line relay 41 of the selector S, Fig. 1, falls back nine times, and each time it does so it closes at armature 51 a circuit through armature 53 and its working contact and series relay 43 for vertical magnet 49. Vertical magnet 49 operates to raise the wipers 62—64 step by step until they stand opposite the ninth level of bank contacts. Relay 43 is operated in series with vertical magnet 49 on the first

impulse of current being delivered to the latter and, being slow acting, maintains its armature attracted throughout the vertical movement. The off-normal contacts 50 close 5 upon the first vertical step of the switch, completing a circuit from the grounded release trunk conductor 6' through armature 54 and its working contact, off-normal contacts 50, interrupter contacts 61, and stepping relay 44 to battery. Relay 44 energizes and closes a locking circuit for itself 10 at armature 55; and at armature 56 prepares a circuit for rotary magnet 48.

At the end of the vertical movement, relay 15 43 falls back and opens the initial circuit of relay 44 at armature 54, leaving this relay energized over its locking circuit which is closed at armature 55. At armature 54 and its resting contact, relay 43 closes a circuit 20 through armature 56 and its working contact for rotary magnet 48. Rotary magnet 48 energizes and advances the wipers 62-64 into engagement with the first set of bank contacts in the level opposite which they 25 were raised during the vertical movement. Near the end of its stroke, rotary magnet 48 opens at the interrupter contacts 61 the circuit of relay 44, which relay falls back and opens a further point in its locking circuit 30 at armature 55 and at armature 56 opens the circuit of rotary magnet 48, whereupon rotary magnet 48 falls back and closes its interrupter contacts again.

From this point the operation depends 35 upon whether the trunk line terminating in the first set of bank contacts is busy or idle. If this trunk line is idle, switching relay 45 energizes right away, seizing the trunk. Assuming that the trunk line is busy, switching relay 45 is short circuited by the ground potential encountered on the busy test contact by test wiper 63 and relay 44 energizes 40 through test wiper 63 and again closes its locking circuit at armature 55, closing the circuit of rotary magnet 56 at armature 48. Rotary magnet 56 energizes again and advances the wipers into engagement with the 45 next set of bank contacts.

This alternate operation of relay 44 and 50 rotary magnet 48 continues in the manner described until an idle trunk is reached, which trunk it will be assumed is the one terminating in bank contacts 65-67. When this idle trunk is reached, switching relay 55 45, being no longer short circuited, energizes from the grounded release trunk conductor 6' through off-normal contacts 50, interrupter contacts 61, and stepping relay 44. Although relay 45 energizes over this 60 circuit, relay 44 does not operate on account of the relatively high resistance of relay 45. Upon energizing, relay 45 opens the test circuit at armature 58 and connects the 65 grounded release trunk conductor 6' to the test wiper 63, thereby making the seized

trunk busy immediately. At armature 59 it disconnects ground from armature 51 of line relay 41, thereby opening the circuit of the slow acting release relay 42; and at armatures 57 and 60 it disconnects conductors 70 5' and 7' from the windings of line relay 41 and extends them by way of wipers 62 and 64 and the bank contact 65 and 67 to the talking conductors of the seized trunk line. The line and release relays associated 75 with the seized trunk line now energize and the latter places ground on the release trunk conductor extending back to and terminating in the test contact 66 so as to maintain the release trunk conductor 6' grounded 80 after the slow acting release relay 42 falls back, as it now does, and after the release relay 9 of the trunk circuit TC falls back, which takes place subsequently.

In the director, the slow acting pick-up 85 relay 241 falls back after the interval for which it is adjusted and opens the circuit of the slow acting relay 242 at armature 288. Stop relay 242 accordingly maintains its armatures attracted for an interval by virtue 90 of its slow action. Relay 241 also removes ground at armature 287 from conductor 31 so that the director may now be released in case the calling subscriber decides to abandon the call and hangs up the receiver. At 95 armature 290, relay 241 completes the connection between the pick-up conductor 216 and relay 232, and at armature 289 it places ground on conductor 217. Accordingly, the setting of the relay register comprising relays 419-422 for the next code digit may 100 now take place as soon as the drum 301, Fig. 4, arrives in its pick-up position.

Assuming that the drum 301 has just 105 passed its pick-up position, and that the setting of the relay register in the director is delayed, the setting of the register may not be completed before stop relay 242 falls back, in which case relay 242 at armature 292 and its resting contact prepares the impulsive 110 circuit of magnet 245, but this circuit is maintained open at armature 274 of the transfer stop relay 239. If, on the other hand, the setting of the relay register has been completed when relay 242 falls back 115 relay 239 is energized with the result that magnet 245 immediately starts to operate under the control of the interrupter 115.

The setting of the relay register for the 120 second code digit will now be described. By referring to the intermediate distributing frame IDF, Fig. 4, it may be seen that the second code digit to be transmitted is the digit 2 on account of the fact that the second bank contact 322 in the set on which the 125 wipers of the office register are standing is cross connected by means of the jumper 324 to the wiper 312 of the drum 301 corresponding to the digit 2. It will be noted that the drum 301 places positive battery on the 130

brush 312 in the A and C positions of the drum.

When positive battery is placed on the wiper 312 in the A position of the drum 301, a circuit is closed from ground through the drum 301, wiper 312, jumper 324, bank contacts 322, wiper 340 of the office register OR, conductor 356, the corresponding contact in the bank of the office register selector ORS, 10 wiper 408, armature 416 and its working contact, conductor 209, armature 264 and its resting contact, armature 266 and its working contact, and polarized relay 235 to the derived neutral tap of the exchange battery. 15 Relay 235 thereupon energizes and at armature 272 places ground on its positive contact, closing a circuit through armature 270 and its resting contact and conductor 210 for the right-hand winding of the A relay 419. 20 Relay 419 energizes and closes at its left-hand armature a locking circuit for its left-hand winding, at the same time shifting its right-hand armatures to bring about the necessary circuit changes.

When the drum 301 advances from its A position to its B position, ground is removed from brush 312 whereupon the polarized relay 235 in the director falls back and opens the initial circuit of relay 419 leaving this 25 relay locked up at its left-hand armature. In its B position, the drum 301 closes a circuit from ground through brush 302 for the positive switching relay 233. Relay 233 energizes and shifts armature 270 from the conductor 210 (leading to the A relay 419) to conductor 212 (leading to the C relay 421).

When the drum 301 arrives in its C position, ground is again placed on wiper 312 with the results that the above described circuit is again closed from positive battery for the polarized relay 235, Fig. 3. When relay 235 energizes at this time and grounds its positive contact at armature 272, it closes a 40 circuit through armature 270 and its working contact and over the conductor 212 for the right-hand winding of the C relay 421, whereupon relay 421 energizes and locks itself at its left-hand armature, and at its 45 right-hand armatures makes the necessary circuit changes.

The code-transfer stop relay 239 is energized and relays 232 and 238 deenergize in the hereinbefore described manner when conductor 216 is grounded the second time.

When the impulsing circuit of relay 245 is closed from the interrupter 115 at armature 374, or at armature 292 and its resting contact, whichever point is completed last, relay 60 245 again starts to energize and deenergize under the control of interrupter 115. The pick-up relay 241 operates again on the first step of wiper 246 as above described. Accordingly, on each succeeding step of the 65 wipers 246 and 247 the outgoing control cir-

cuit is opened at contacts 243. The second interruption in the outgoing control circuit occurs when the wiper 247 is standing on the second bank contact, which is the one in which the first impulse stop conductor 70 terminates. When magnet 245 falls back and terminates the second interruption in the outgoing control circuit, wipers 246 and 247 advance one step in the usual manner and wiper 247 closes a circuit for stop relay 242 75 as follows: From ground by way of the right-hand armature and its working contact of the A relay 419, Fig. 5, middle armature and resting contact of the B relay 420, middle armature and its working contact of 80 the C relay 421, the second impulse stop conductor, the third contact in the bank of wiper 247, and stop relay 242 to battery. The energization of stop relay 242 results in the termination of the digit being transmitted and in the restoration of relay 239 85 and the relays of the relay register, Fig. 5, in the hereinbefore described manner.

The transmission of the second digit 2 results in the selector switch controlled over the trunk line seized by the selector S in response to the first digit raising its wipers to the second level and selecting an idle trunk line leading to the desired office.

In the director, the setting of the relay register again starts in the hereinbefore described manner when pick-up relay 241 falls back, the wipers 112 and 113 of the sequence switch S' now being in their third position. When pick-up relay 232 pulls up responsive 95 to the arrival of the drum 301, Fig. 4, in its pick-up position, it again connects up the associated polarized relay to receive the impulses from the drum. In this case, since two code digits are sufficient to trunk the 100 call to the desired office, the third and fourth code-digit positions are not used for the transmission of code digits and it is necessary to arrange for these positions to be skipped by the sequence switch S'. Therefore, the third contact 333 in the contact set 105 on which the wipers of the office register are now standing is connected by means of the jumper 325 to the skip brush 306 of the drum 301. By referring to the table shown 110 in Fig. 9, it will be noted that the skipping operation requires that the relays A, B, and C be operated. Also by referring to the showing of the drum 301 it will be noted that current is supplied to brush 306 in the 115 A, B, and C positions of the drum. That being the case, the A, B, and C relays 419, 420, and 421, respectively, of the relay register, Fig. 5, are energized in the hereinbefore described manner through the action of 120 the polarized relay 325 and the switching relays 323 and 324.

With relays 419, 420 and 421 energized, a circuit is closed through normally open contacts on the relays mentioned, and over con- 130

ductor 206 for skip relay 114. Relay 114 energizes and opens a point in the interrupter circuit at armature 117, and at armature 116 closes a circuit through the third contact in the bank of wiper 112 and the said wiper, and the self-interrupting contacts 111 for the stepping magnet 110 of the sequence switch S' . That being the case, magnet 110 operates in a buzzer-like manner to advance the wipers 112 and 113 until wiper 112 passes off the fourth bank contact and lands on the fifth associated contact. The upper winding of relay 231, Fig. 3, now energizes over conductor 205, the fifth contact in the bank of wiper 112 and the said wiper, contacts 111 and through the magnet 110. Magnet 110, however, does not operate on account of the relatively high resistance of the upper winding of relay 231. Relay 231 operates and closes a locking circuit for its lower winding at armature 251; places a shunt around armature 274 and its working contact at armature 250 so as to operate subsequently the magnet 245 from the interrupter 115 independent of the energization of the transfer stop relay 239; removes ground at armature 249 from conductor 217; at armature 264 disconnects conductor 209 leading to wiper 113 of the sequence switch S' from the polarized relay 235 and connects it to ground instead; at armature 63 places ground on release conductor 204; at armature 261 breaks a further point in the original test circuit of the office register selector ORS; and at armature 262 opens the initial energizing circuit of relay 402 of the office register selector ORS leaving relay 402 locked up in a circuit which includes off-normal contacts 346, conductor 354, contact in the bank of wiper 406 and the said wiper, and armature 414 and its working contact.

Responsive to the above mentioned grounding of release conductor 204 by relay 231, Fig. 3, at armature 263, a circuit is closed through the working contact and armature 413, wiper 405, and the bank contact on which it is standing and conductor 353 for release magnet 345. Release magnet 345 energizes over this circuit and restores the wipers 339-342 to their normal position. When the normal position is reached, off-normal spring 346 is separated from its associated contact, removing ground from conductor 354. Relay 402 now falls back and disconnects the associated wipers and at armature 414 opens a further point in its own locking circuit.

Responsive to the grounding of wiper 113 of the sequence switch S' through conductor 209 and at armature 264 of relay 231, a circuit is closed through the fifth contact in the bank of wiper 113 and over conductor 131 and through the normal contact in the bank of the wiper of the digit register

DR-1 and conductor 219 for stop relay 243, Fig. 3, in case the digit register DR-1 has not yet been operated. In this case relay 242 pulls up to prevent the starting of the sending switch SS for a definite length of time following the starting of the operation of the digit register DR-1.

As a result of the removal of the ground potential from the locking conductor 217 at armature 249 of relay 231, the relays, including relays 419-421, Fig. 5, which are locked up by this conductor are unlocked and fall back, the latter relays opening the circuit of the skip relay 114, Fig. 2. Relay 114 is slow acting and for that reason maintains armatures 116 and 117 attracted for an interval after which it falls back and at armature 117 completes a point in the sending circuit of magnet 245 of the sending switch SS. The reason for the delay in the falling back of relay 114 and in the closing of the sending circuit is to permit the digit register DR-1 to become sufficiently advanced before the sender is started in case the digit register moves off its normal contacts just as relay 231 is about to pull up and ground wiper 113 at armature 264 to close a holding circuit for relay 242, Fig. 3, as previously mentioned. The delay occasioned by relay 114 is of course a special delay, but the delay governed by the time required for the stop 242, Fig. 3, to fall back may take place on any one of the following digits.

When the sending circuit is finally completed, the sending switch SS is again started and transmits the digit registered on the digit register DR-1. The stop relay 242 is energized over the following circuit to terminate the digit: From ground by way of the working contact and armature 264 of relay 231, Fig. 3, conductor 209, wiper 113, the fifth associated bank contact, conductor 131, wiper of the digit register DR-1, the bank contact on which it was set by the calling subscriber, the associated impulse stop conductor, the corresponding contact in the sender bank, wiper 247 and relay 242 to battery. The energization of relay 242 results in the termination of the digit in the usual manner. The sequence switch S' is, of course, advanced one step at the termination of this digit, and wiper 113 removes the ground from the wiper of the digit register DR-1 and extends it over conductor 132 to the wiper of the digit register DR-2.

As soon as the pick-up and stop relays 241 and 242 fall back, the sending switch SS is started to transmit the digit registered on the digit register DR-2 in case the said register is operated.

The above described operation of the sending apparatus and of the sequence switch S' continues as described until the digit stored on the digit register DR-4 is transmitted.

and is terminated upon the pulling of the stop relay 242 over conductor 134 and the wiper of the digit register DR-4. When this occurs, the wipers 112 and 113 of the sequence switch S' are again advanced one step in the hereinbefore described manner and wiper 113 engages its last bank contact and places ground on conductor 32. When this occurs, a current flows over conductor 32 through contact in the bank of wiper 28 and said wiper of the director selector DS, Fig. 1, armature 24, armature 12 and its working contact, and through the switching relay 10. Relay 10 responds to this flow of current and closes a locking circuit for itself at armature 17, and at armatures 16 and 18 disconnects conductors 5 and 7 from the windings of line relay 8 and connects them instead to conductors 5' and 7' of the selector S, at the same time disconnecting conductors 5' and 7' from the closed loop of the director. Line relay 8 falls back and at armature 11 opens the circuit of the slow acting release relay 9. Relay 9 energizes after a slight interval and removes ground from the release trunk conductor 6 at armature 13, leaving this conductor grounded through bank contact 66, wiper 63, and armature 58 and its working contact of the selector S. At armature 18, relay 9 opens a further point in the test circuit of the director selector DS, and at armature 14 it opens the circuit of switching relay 19, whereupon relay 19 falls back, freeing the director.

The removal of ground from release trunk conductor 31, Fig. 3, when the director is freed, opens the circuit of the lower winding of relay 231 and opens the circuit of the relay 240. Relay 240 falls back immediately but relay 231 is maintained operated momentarily over its upper winding. Upon falling back relay 240 opens further points in the operating circuit of the office register selector ORS at armatures 278 and 279; grounds the release conductor 204 at armature 280 (without any particular utility at this time); and at armatures 281, 282 and 283 grounds the restoring conductors 205, 206 and 218. The grounding of the restoring conductor 206 does not have any utility at this time as the wipers 112 and 113 of the sequence switch S' have passed the contacts controlled by conductor 206. However, the grounding of conductor 205 results in the advance of the wipers 112 and 113 of the sequence switch S' the remaining step to their normal position.

The grounding of conductors 218 results in the closure of circuits for the release magnets of the digit registers DR-1-DR-4 and for the release magnet 106 of the sequence switch S, Fig. 2. Release magnet 106 restores the wipers 108 and 109 to their normal position, whereupon its circuit is opened at

off-normal contacts 107. The digit registers DR-1-DR-4 are released in the same manner. The director is now in the normal position shown in the drawings and is ready to be used in handling another call. 70

When the calling subscriber replaces his receiver at the end of the conversation, ground is removed from the release trunk conductor of the established connection, whereupon relay 45 of the selector S and relay 10 of the trunk circuit TC fall back. At armature 59, relay 45 closes a circuit through armatures 51 and 53 and off-normal contacts 45 for release magnet 47. The energization of release magnet 47 over this circuit results in the restoration to normal of the wipers 61-64, whereupon off-normal contacts 46 open the circuit of release magnet 47. 75

Considering now a case in which the director shown in Figs. 2, 3, 5 and 6 is used in conjunction with an office register, such as the office register OR, Fig. 4, to handle calls in which a maximum number of code digits are required, the resetting of the relay registers comprising relays 419-422 continues following the transmission of each of the code digits in the manner described hereinbefore, and the operation of the sender continues until the termination of the fourth code digit at which time the sequence switch S' advances its wipers 112 and 113 into engagement with the fifth set of bank contacts. This happens of course with relays 241 and 242 energized, as it occurs responsive to the energization of stop relay 242, as hereinbefore described. Relay 231 energizes responsive to the closure of the usual circuit for its upper winding over conductor 105 from battery through magnet 110, and wiper 112, and closes at armature 250 a point in the sending circuit of the sending switch SS. This circuit, however, remains open at armature 292 of stop relay 242, Fig. 3, until stop relay 242 falls back. Furthermore, ground is placed on wiper 113 at armature 264 of relay 231 with the result that if the digit register DR-1 is still in its normal position the stop relay 242, Fig. 3, is held energized to prevent the sending operation from taking place until a sufficient time is elapsed following the beginning of the operation of the wiper of the digit register DR-1 for the reason hereinbefore given. 110

It will be assumed now that the trunk circuit TC is seized as hereinbefore described; that the director selector DS seizes the director shown in the drawing; that the office register selector ORS seizes the office register OR, Fig. 4, and that the office register OR is operated to bring the wipers 339-342 into engagement with the bank contacts 335-338. It will be noted that the first three contacts in this set are cross connected to the fourth, sixth and third digit termi- 115 120 125 130 135 140 145 150 155 160 165 170 175 180 185 190 195 200 205 nals, respectively, on the left-hand side of the intermediate distributing frame IDF so as to bring about the transmission of the code 463. It may be assumed that the bank contacts 335—338 are assigned to an operator's switchboard, for example the switchboard of the toll recording operator which is reached from selector banks by the transmission of the code 463. That being the case, no further digits are required and it is desired to operate the switching relay of the trunk circuit TC to switch the connection through and free the director at the end of the transmission of the third code digit 3. Accordingly, the fourth bank contact 338 is cross connected by means of the jumper 330 to the switching terminal on the left-hand side of the intermediate distributing frame IDF, which terminal represents in the switching brush 305 of the drum 301. Therefore, when the fourth wiper of the office register is connected up the following transmission of the third code digit, current impulses are transmitted over the switching brush 305 in the A, B, and D positions of the drum 301, to set the A, B, and D relays 419, 420, and 422, respectively, of relay register, Fig. 5, in accordance with the code given in Fig. 9. With these three relays operated, a ground potential is extended to the switching conductor 32 with the result that switching relay 10 of the trunk circuit TC, Fig. 1, energizes over its circuit hereinbefore traced and switches the connection through and frees the director. In this case it will be noted that the office register selector ORS is freed and the office register OR is released by the action of the release relay 240 rather than by the action of relay 231 as hereinbefore described.

Referring now to Fig. 7, this drawing shows a modification of the office register OR and of the office register selector ORS to permit a reduction in the number of wipers of the office register selector ORS from eight wipers as shown in Fig. 5, to six wipers as shown in Fig. 7. In Fig. 7, the parts which are numbered that also appear in the other drawings have the same numbers as they have in such other drawings. When this office register selector ORS, modified as shown in Fig. 7, is used it operates in the hereinbefore described manner under the control of test wiper 406 to select an idle office register when the associated director is seized. Assuming that the office register OR is the one selected, relay 402 pulls up when this idle office register is reached and connects up the associated wipers. When wiper 408 is connected up at armature 416, a circuit is closed from off-normal springs 346, contact in the bank of wiper 408 and said wiper, armature 416 and its working contact, conductor 128, conductor 606, first contact in the bank of wiper 108, and wiper

108 to battery. Relay 601 energizes over this circuit and locks itself at armature 602 independent of off-normal spring 346 and its lower contact; disconnects wiper 340 at armature 603, and at armatures 604 and 605 disconnects conductors 357 and 358 from wipers 341 and 342, and connects them instead to the rotary and vertical magnets 344 and 343, respectively. 70

When the first digit is dialled, the impulses of current are transmitted over the usual path to wiper 109 and thence by way of conductors 121 and 130, working contact and armature 418, wiper 410, the bank contact on which it is standing, conductor 358, 80 and armature 605 and its working contact to vertical magnet 343. Accordingly, the vertical magnet 343 operates to raise the wipers 339—342 opposite the desired level of bank contacts. Off normal spring 346 is shifted on the first vertical step of the office register to ground the release trunk conductor 354, and it opens the initial circuit of relay 601, leaving relay 601 energized over armature 602 and its working contact. 90

The wipers 108 and 109 of the sequence switch S are advanced one step in the usual manner at the end of the first digit, and wiper 109 moves from its first contact to the second contact to connect the impulsing conductor to conductor 122. 95

When the second digit is dialled, the impulses of current are transmitted through conductor 122, conductor 129, working contact and armature 417, wiper 409 and the bank contact on which it is standing, conductor 357, and armature 604 and its working contact to rotary magnet 344. Accordingly, rotary magnet 344 operates to advance the wipers 339—342 in a rotary direction 105 into engagement with the desired set of bank contacts.

The wipers 108 and 109 of the sequence switch S are advanced one step at the end of the second series of impulses, and wiper 108 removes battery from conductor 606 and places it on the start conductor 208, whereupon relay 601, Fig. 7 falls back and connects conductors 356, 357, and 358 to the corresponding wipers 340, 341, and 342, at the same time disconnecting conductors 358 and 357 from the vertical and rotary magnets of the office register. 110

The remaining part of the operation is the same as described hereinbefore. 120

Referring now to Fig. 8, this drawing shows a modification similar to that shown in Fig. 7 except that the wiper 405 also has been removed from the office register selector. Corresponding changes have been made in the office register to permit it to operate satisfactorily without the releasing wiper 405. 125

The operation of the modification shown in Fig. 8, will now be described. When the office register selector ORS seizes the office 130

register OR, relay 402 pulls up and connects up the wipers 407—410 and at armature 414 disconnects test wiper 406 from the test conductor 201 and connects it to ground directly instead of to conductor 203 as in Figs. 5 and 7. When wiper 406 is grounded, a circuit is closed through the normally closed contacts controlled by armature 704 of the two step relay 701, Fig. 8, and through off normal contact 346 and its lower contact for the two windings of relay 701 in series. The lower winding of relay 701, however, is short circuited at this time by the battery potential applied from wiper 108 of the sequence switch S through the first bank contact, conductors 606 and 128, working contact and armature 416, wiper 408 and the bank contact on which it is standing, conductor 356, and armature 705 and its resting contact. That being the case, the two step relay 701 energizes only partially on account of the fact that its upper winding consists of a relatively small number of turns of wire having a comparatively high resistance per turn. Armature 703 is moved out of engagement with its resting contact. Armature 704 is moved into engagement with its working contact and the normally closed contacts controlled thereby are opened. Armatures 705, 706, and 707 are not operated. Armature 703 opens a point in the circuit of release magnet 345, and armature 704 locks relay 701 to the release trunk conductor 354 and disconnects the said conductor 354 from off-normal spring 346.

When the first digit is dialled, the impulses of current delivered to wiper 109 of the sequence switch S are transmitted by way of conductors 121 and 130, working contact and armature 418, wiper 410 and the bank contact on which it is standing, conductor 358, and armature 707 and its resting contact to vertical magnet 343. The vertical magnet 343 operates in the usual manner to raise the wipers of the office register opposite the desired level of bank contacts.

The second series of impulses is transmitted over conductors 122 and 129 and through the working contact and armature 417, wiper 409 and the bank contact on which it is standing, conductor 357, and armature 706 and its resting contact to the rotary magnet 344, which operates to rotate the wipers of the office register into engagement with the desired set of bank contacts.

When the wipers of the sequence switch S advance at the end of the second digit, battery is removed by wiper 108 from conductor 606 and is placed on start conductor 208. When this occurs, the lower winding of the two-step relay 701, Fig. 8, is no longer short circuited and this relay energizes fully, operating the armatures 705—707 to disconnect conductors 356—358 from their local connec-

tions and to extend them to the wipers 65 340—342, respectively.

When ground potential is removed from conductor 203 by the director in the usual manner, relay 402 immediately falls back and removes ground from wiper 406 at armature 414. Relay 701 of the office register OR responds by restoring all of its armatures to the normal position shown in the drawing. The normally closed contacts controlled by armature 704 replace ground on conductor 354 from off normal spring 346 and its upper contact so as to guard the office register OR against seizure from an office register selector similar to ORS until the restoration to normal has been completed. At armature 703 relay 701 closes a circuit through off-normal contacts 702 for release magnet 345. The energization of release magnet 345 results in the restoration of the wipers 339—343 to their normal position in the usual manner, whereupon the circuit of release magnet 345 is opened at off-normal contacts 702. Furthermore, off-normal spring 346 disconnects conductor 354 from ground and again connects it to relay 701. The office register OR is now ready for seizure again.

What is claimed is:

1. In combination, an office register, a storage device, a sender, a plurality of circuits prepared by setting said office register, means for setting the storage device over each circuit in turn, said means being controlled exclusively over the circuit in use in each case regardless of the setting of the office register, and means for causing the storage device to control the sender each time it is set.

2. In combination, an office register, a storage device, a sender, a plurality of circuits prepared by setting said office register, an impulse machine for transmitting a variable series of code impulses over each circuit in turn to set said storage device a plurality of times, once over each circuit, and means for causing said storage device to control said sender each time it is set.

3. In a telephone system, a director for routing a call in accordance with a code derived from the office designation in the called number, an office register for registering the office designation, said office register having a wiper for each code digit, means associated with said office register for transmitting characteristic impulses through each of the office register wipers in turn to the director, whereby a separate code digit is transferred to the director over each wiper, a receiving device in said director responsive to such impulses, and means in the director controlled by said receiving device for retransmitting each digit before the next digit is received.

4. In a telephone system, means for registering called numbers, said means including an office register adapted to be set in accordance with the office designating portion of 5 a number, a plurality of wipers on said office register, a storage device, means for setting said device over each wiper in turn in accordance with digits derived from the office designation, means for transmitting 10 each digit when stored, and means for releasing the storage device each time it is transmitted to prepare for the storage of the next digit.
5. In a telephone system, a plurality of 15 primary registers, a plurality of secondary registers, a device for generating positive and negative impulses, means for setting any one of said primary registers, and means including a polarized relay operated by said 20 impulses in accordance with the setting of said primary register for setting one of said secondary registers.
6. In a telephone system, a primary register, a secondary register comprising a plurality of relays, a device for generating positive and negative current impulses, a polarized relay having positive and negative contacts leading to said secondary register, means for operating said primary register 25 to effect a connection between said sending device and said polarized relay whereby said relay is operated by certain of said impulses, and switching relays controlled by said device over circuit paths independent of said 30 primary register to alter the connection between the said positive and negative contacts and the relays forming said secondary register.
7. In a telephone system, primary and 35 secondary registers, a controlling device for controlling said secondary register in accordance with the setting of said primary register, said device having a pick-up position and a number of other positions, means responsive to the arrival of said controlling device in its pick-up position to prepare 40 circuits for setting said secondary register in the other positions of said device, sending mechanism controlled by said secondary 45 register, and means responsive to the arrival of said controlling device in its pick-up position the second time for starting said sending mechanism.
8. In a telephone system, a plurality of 50 directors for controlling the establishment of connections, digit registers individual to each director, and office registers common to said directors.
9. In a telephone system, a plurality of 55 directors for controlling the establishment of connections, digit registers individual to each director, office registers common to said directors, and means included in each director and automatically responsive when the same 60 is taken for use for selecting an idle office register.
10. In a telephone system, a plurality of directors for controlling the establishment of connections, digit registers individual to each director, office registers common to said 65 directors, and means responsive to the seizure of a director by a calling subscriber for connecting such director with an idle office register.
11. In a telephone system, a plurality of 70 directors for controlling the establishment of connections, digit registers individual to each director, office registers common to said directors, means responsive to the seizure of a director by a calling subscriber for connecting such director with an idle office register, 75 means effective after the office register is set for transferring the registration to the director, and means effective upon the completion of the transfer for returning the office register to common use.
12. In a telephone system, a plurality of 80 directors for controlling the establishment of connections, digit registers individual to each director, office registers common to said directors, means responsive to the seizure of a director by a calling subscriber for connecting such director with an idle office register, means effective after the office register is set for transferring the registration to the director, 85 means effective after the office register is set for transferring the registration to the director in the form of a code, the several digits of the code being transferred one at a time, means in the director for transmitting each digit as received, and means for restoring the office register to common use when the transfer of the code is completed.
13. In a telephone system, a director, means for seizing said director, a plurality of office registers, an office register selector individual to said director responsive to the 90 seizure of said director to seize an idle one of said office registers, means for setting the seized office register in accordance with the office designation in the wanted number, subscriber digit registers in said director responsive to the subscriber digits of the number, sending mechanism in said director controlled first according to the setting of the seized office register and subsequently according to the setting of said subscriber digit 95 registers to transmit series of impulses, and means responsive to the operation of said sender in accordance with the setting of said office register for releasing said office register selector to free said seized office register.
14. In a telephone system, an office register, a plurality of digit registers, a sender for transmitting impulses as determined by the setting of said registers, a sequence switch for placing said sender under the control of said registers successively, a plurality of 100 positions of said sequence switch being assigned to said office register whereby said 105
15. In a telephone system, a plurality of 110 directors for controlling the establishment of connections, digit registers individual to each director, office registers common to said directors, and means included in each director and automatically responsive when the same 115 is taken for use for selecting an idle office register.
16. In a telephone system, a plurality of 120 directors for controlling the establishment of connections, digit registers individual to each director, office registers common to said directors, means responsive to the seizure of a director by a calling subscriber for connecting such director with an idle office register, 125 means effective after the office register is set for transferring the registration to the director, and means effective upon the completion of the transfer for returning the office register to common use.

- sender is placed under the control of said register a number of times, and means for automatically advancing said sequence switch past one or more of said office register positions without a control of said sender being effected in such positions, and for preventing the sending operation of said sender for a pre-determined length of time following such advancing operation.
- 10 15. In a telephone system, an office register, a plurality of digit registers, a sender for transmitting impulses as determined by the setting of said registers, a sequence switch for placing said sender under the control of said registers successively, a plurality of positions of said sequence switch being assigned to said office register, whereby said sender is placed under the control of said office register a number of times, a slow-acting skip relay, means controlled through said office register following the transmission of a digit by said sender under the control of said office register for energizing said skip relay to automatically advance 75 said sequence switch through the remaining office-register position, and means controlled by said skip relay to prevent further operation of said sender until said skip relay falls back.
- 15 20. In a telephone system, a director, an office register, means for seizing said director, means responsive thereto for seizing said office register, means for operating said office register, a release magnet for said office register, a circuit for said release magnet including a conductor in said director, means in said director for closing said release magnet circuit and for canceling the seizure of said office register, and means in said office register for maintaining its seizure independent of said director until the operation of said release magnet is completed.
- 20 25. In a telephone system, a first automatic switch and a plurality of other automatic switches, means for extending a connection to said first automatic switch, means responsive thereto for operating said first automatic switch to further extend the connection to an idle one of said automatic switches, a test conductor for said idle switch, means at said first automatic switch responsive to the completion of the connection to said idle switch for placing a guarding potential on said test conductor, means controlled over said connection for operating the last named switch, off-normal contacts in said last named switch for applying a second guarding potential to said test conductor, and means independent of said test conductor for releasing said last named switch and for removing the first guarding potential from said test conductor, whereby said test conductor is maintained guarded until said last named switch reaches its normal position.
- 25 30. In a director system, an office register, a switch for selecting said register, circuits for operating the register, other circuits over which digits are transferred back, conductors extending through the switch, and means whereby each conductor is included in an operating circuit and also in a digit transfer circuit.
- 30 35. In a telephone system, first and second automatic switches, means for operating said first switch to extend a connection to said second switch, said connection including a conductor extending through said first switch to a wiper of said second switch, an operating magnet for said second switch, a relay in said second switch energized through another conductor of said connection to disconnect said first conductor from said wiper and to connect it to said operating magnet, means controlled from said first automatic switch over said first conductor to operate said magnet to position the wipers of the second switch on a desired contact set, and means in said first automatic switch for then opening the circuit of said relay to shift said first conductor back to said wiper again.
- 35 40. In a telephone system, first and second automatic switches, means for extending a connection from said first switch to said second switch, a conductor of said connection extending from the bank of said switch to a wiper of said second switch, a relay, a source of current, a connection from said conductor in said second switch through said relay and through off-normal contacts of said second switch to one pole of said source of current, connections from said conductor in said first switch to the other pole of said source of current, whereby said relay is operated to disconnect said conductor from the associated wiper and to by-pass said off-normal contacts, means for operating said second switch to open said off-normal contacts, and means in said first switch effective while said connection between said switches is maintained for disconnecting the associated pole of said current source from said conductor whereby said relay is operated to reconnect said conductor to said wiper and to open the connection between said conductor and the said one pole of said source of current.
- 40 45. In a director system, an office register, a switch for selecting said register, circuits for operating the register, other circuits over which digits are transferred back, conductors extending through the said switch and normally included in said operating circuits, and means whereby the said conductors are included in said transfer circuits after the register is operated.

22. In a telephone system, first and second automatic switches, means for extending a connection from said first automatic switch to said second automatic switch, a conductor 5 of said connection extending to an operating magnet of said second automatic switch, a second conductor of said connection extending a given potential to one winding of a relay in said second switch, a third conductor 10 of said connection extending the opposite potential to said winding, whereby current flow in said winding is prevented, means for transmitting current impulses over the first named conductor to operate said magnet to 15 set said switch, and means in said first switch for then opening the second connection whereby said relay is operated to disconnect the first named conductor from said magnet and to connect it to said wiper.
23. In a telephone system, sending devices 20 each including counting means, a registering device common to all said sending devices, means responsive to a sending device being taken for use for rendering said register temporarily individual to such sending device 25 to control its counting means.
24. In a telephone system, sending devices each including counting means, a registering device common to all said sending devices, 30 means responsive to any sending device being taken for use for rendering said register temporarily individual to such sending device to control its counting means.
25. In combination, sending devices for 35 controlling the extent of movement of automatic switches, said devices including testing means for regulating the extent of the control exercised, a registering device common to said senders and arranged to control 40 the testing device of any sender to which it is connected, and means for automatically effecting a connection between a sending device and said register.
26. In combination, counting devices, a 45 directly controlled register common thereto, and means for automatically effecting a connection between said register and any device, for exercising the directive control of said register through such connection, and 50 for subsequently controlling said device through such connection in accordance with the set position of said register.
27. In a telephone system, a trunk line, 55 automatic switching mechanism for setting up connections including said trunk line, directors arranged to control said mechanism, a registering device common to the directors arranged to influence the control exercised by any director to which it is connected, means for connecting any director to 60 said trunk line when a connection is to be extended thereover, means for connecting said register to the connected director through a circuit path excluding said trunk line, and means for subsequently setting said 65 register over said trunk line through the connected director.
28. In a telephone system in which calls are set up through automatic switches under the control of directors, office registers common to the directors, means for effecting a non-numerical trunking operation for associating a director with an automatic switch to be operated, and means for effecting a further nonnumerical trunking operation for 70 associating an idle office register with such director.
29. In combination, a plurality of primary registering devices, means for setting said devices, a secondary registering device, a device common to said primary registers for generating positive and negative impulses, and means for setting said secondary register in accordance with the setting of any operated primary register through the 75 medium of the impulses generated by said device and in a position corresponding to the setting of the last named primary register.
30. In combination, a plurality of primary registers, a plurality of secondary registers, means for temporarily associating any primary register with any secondary register and for temporarily associating any other primary register with any other secondary register at the same time, a generating device common to said primary registers for generating positive and negative impulses, and means for operating said generating device to generate impulses to set 80 the secondary registers simultaneously and into the respective positions indicated by the setting of the associated primary registers.
31. In a telephone system, a plurality of primary registers, a director including a 85 secondary register, a device for generating positive and negative impulses, means included in said director for setting any one of said primary registers, and means including a polarized relay operated by said impulses in accordance with the setting of said primary register for setting said secondary register.
32. In a telephone system, a plurality of directors, office registers common to said directors, and a hunting switch individual to each director and automatically responsive when the same is taken for use for selecting an idle office register.
33. In a multi-office telephone system, a 100 call director, a plurality of office registers each operable to register office digits in telephone numbers, and automatic switching mechanism operable to connect any one of said office registers with said director.
34. In a multi-office automatic telephone system, trunk lines, directors for controlling the operation of the automatic switches, said 105

directors being common to said trunk lines, office registers common to said directors, means for connecting any idle director to a trunk line when a connection is to be extended thereover, and means for connecting an office register to the connected director over a path excluding the connection between the director and trunk line.

35. In a telephone system, automatic switches for extending connections from calling lines in one office to called lines in other offices, directors in the first office for controlling said switches, office registers for said directors assembled in a group apart from said directors, automatic switching mechanism for effecting connections between said office registers and said directors, and means for setting said office registers over said connections.

20 36. In a telephone system, automatic switches for extending connections from calling lines in one office to called lines in other offices, directors in the first office for controlling said switches, office registers for said directors, said registers being assembled in a group apart from said directors, multiple connections between the banks of said registers, and automatic switching mechanism for effecting connections between said office registers and said directors.

35 37. In a telephone system, automatic switches for extending connections from calling lines in one office to called lines in other offices, directors in the first office for controlling said switches, office registers for said directors assembled in a group apart from said directors, multiple connections between the banks of said registers, two operating magnets in each office register, automatic switching mechanism for effecting connections between said office registers and said directors, an impulse conductor in each director over which the magnets of any connected office register may be operated, and a steering switch associated with said impulse conductor for associating it with the operating magnets of a connected office register successively.

40 38. In a multi-office telephone system, a director for controlling the establishment of telephone connections, an office register, automatic switching mechanism for closing a connection between said office register and said director when the director is to be used, primary and secondary operating magnets in said office register, conductors included in the connection between the register and the director leading to said magnet, a steering switch in said director, means for sending two series of impulses to said steering switch, and means for operating said steering switch so that the first series of impulses is transmitted over one conductor to the corresponding magnet of the register and the other series of impulses is transmitted

over the other conductor to the other magnet of the register.

39. In a telephone system, a plurality of directors for controlling the establishment of connections, digit registers individual to each director, office registers common to said directors, and means for automatically associating an office register and a director with each other.

40. In combination, a plurality of terminals corresponding respectively to a plurality of characters to be transmitted by transmitting impulses, a conductor over which said impulses are to be transmitted, means for connecting said conductors to any one of said terminals to predetermine a character, a switching conductor, means for transmitting a switching impulse over said switching conductor between impulses of a character being transmitted, a receiving device controlled jointly over said first conductor and said switching conductor to receive the transmitted character, a pickup conductor extending between said sending device and said receiving device, and means included in the sending means for transmitting a pickup impulse over said pickup conductor between successive character transmissions, and means in the receiving device responsive to a pickup impulse to render the receiving device receptive.

41. In combination, a first sender having a plurality of terminals to which a plurality of different impulse combinations are repeatedly delivered, respectively, a receiving device, means including a register for connecting said receiving device to any one of said terminals, a pickup conductor extending between said sending device and said receiving device, means controlled over said pickup conductor from said sending device for rendering said receiving device receptive at the beginning of impulse transmission, and a second sending device controlled from the receiving device and in accordance with the character received.

42. In combination, a device arranged to transmit impulses differing as to polarity and as to time of transmission, a receiving device connected to said transmitting device, said receiving device being polarized so as to differentiate between the impulses as to polarity, and means in the receiving device controlled over a separate connection between the transmitting and receiving devices for distinguishing between the impulses as to time.

43. In combination, an impulse transmitter, an impulse receiver, said transmitter being operable to transmit an impulse of either of two polarities and during any one of a plurality of time intervals, and means in the receiving device controlled over a plurality of separate circuits over separate conductors connecting the transmitting device

and receiving device for recording the polarity of the impulse and for recording the time period of the impulse.

44. In a register sender, a registering device having a plurality of wipers, conductors each representing a different character and arranged in miscellaneous groups, means for operating said registering device to effect a connection through its wipers to any one of said groups of conductors, storing apparatus in said register sender operated under the control of said wipers to store a character for each wiper of said register, the characters stored in any case depending upon the conductor with which the wiper is connected, and means for placing said storing apparatus under the control of said wipers successively.

45. In combination, a register sender, a storage device in said register sender and a sending device controlled by the storage device, a transmitter, a primary register, means for operating said primary register in accordance with the desired operation of said sender, means for setting said storage device in accordance with the position assumed by the primary register, said means including a transmitter to which a connection is extended by the primary register, and a pick-up relay associated with said storage device and controlled by said register.

46. In combination, an office register having wipers, a variably adjustable sender controller, a sender controlled thereby, means effective after said office register has been set for adjusting said controller over the respective wipers successively, each adjustment

being effected over the wiper in use exclusive of the other wipers, and means for operating said sender after each adjustment and in accordance therewith. 40

47. In combination, a storage device and a sender controlled thereby, means for alternately setting said device and operating said sender, an office register having a plurality of wipers, each setting of said storage device being effected through a separate one of said wipers and exclusive of any other wiper. 45

48. In a register sender for use in a multi-office telephone system, a register set in accordance with an office designation, said register having wipers, a storage device, means for setting said storage device as many times as there are wipers on said register, each setting being controlled in each case over a 50 separate wiper. 55

49. In a register sender for use in a multi-office telephone system, a register arranged to be set in accordance with an office designation, said register having wipers, storage 60 apparatus arranged to respond to a setting of said register to store any one of ten digits per wiper, each digit stored being received over the corresponding wiper independent of any other one of said wipers, a sender, 65 and means for operating said sender in accordance with the stored digits.

In witness whereof, I hereunto subscribe my name this 22nd day of August, A. D. 1925.

JOHN I. BELLAMY.

In witness whereof, I hereunto subscribe my name this 22 day of August, A. D. 1925.

RODNEY G. RICHARDSON.
